[57] **CLAIM**

The ornamental design for a bidet, as shown and described.

DESCRIPTION

FIG. 1 is a perspective view taken from the top, front and left side of a bidet embodying our new design;

FIG. 2 is a top plan view thereof;

FIG. 3 is a left side elevational view thereof, the right side being the mirror image of the left side; and,

FIG. 4 is a front elevational view thereof.

The fragmentary broken line representations of holes in FIGS. 1 and 2 are for the purpose of illustration only and form no part of the claimed design.

FIG. 1

FIG. 2

FIG. 3

FIG. 4
